UNITED STATES PATENT OFFICE.

FREDERICK ALBERT STRASSWEG, OF EVANSVILLE, INDIANA.

MARINER'S COMPASS.

No. 835,840.

Specification of Letters Patent.

Patented Nov. 13, 1906.

Application filed July 10, 1906. Serial No. 325,465.

To all whom it may concern:

Be it known that I, FREDERICK ALBERT STRASSWEG, a citizen of the United States of America, residing at Evansville, in the county of Vanderburg and State of Indiana, have invented certain new and useful Improvements in Mariners' Compasses, of which the following is a specification, reference being had therein to the accompanying drawings.

This invention relates to mariners' compasses adapted especially for use with submarine vessels.

As the ordinary compass is not reliable in operation when submerged, my invention provides a tower to be carried by a submarine boat having a compass supported thereon above the surface of the water, in combination with means for indicating the movements of the compass-needle upon a suitable annunciator on board the boat, said means being under control of an operator on the vessel.

The construction of the improved compass will be fully described hereinafter in connection with the accompanying drawings, which form a part of this specification, and its features of novelty will be defined in the appended claims.

In the drawings, Figure 1 is a view in perspective of a compass embodying the invention. Fig. 2 is a central vertical section of the same, and Fig. 3 is a view in perspective, on an enlarged scale, of the needle-guide and a circuit-closer employed therewith.

The reference-numeral 1 designates the upper portion of a tower of skeleton construction adapted to be carried by a submarine boat and of sufficient height to project above the surface of the water after the boat is submerged. The tower 1 is provided with oppositely-disposed cleats 2 to support a box or casing 3, containing a part of the mechanism employed in connection with the compass.

Secured to the top of the tower is a bowl 4, constituting the supporting-base of the compass and having its upper surface centrally countersunk or recessed to provide a chamber 5 and a contracted vertical passage 6. The base 4 is also formed with an inclined passage 7, leading from the chamber 5 through the adjacent side of the base, and at each side of the central passage 6 is formed a contracted passage 8.

Resting upon the top of the base 4 is a

frame comprising inwardly-inclined standards 9, connected at their upper ends by a plate 10, surmounted by a knob 11, centrally bored and screw-threaded for the passage of a rod 12, the lower end of which is pointed to adapt it to serve as the upper pivot for the needle 13 of the compass. The lower pivot-rod 14 for the needle extends upward through a tube 6^a, located within the central passage 6, and through the chamber 5, the lower portion of said base having a threaded passage-way 15 for the threaded end of the said rod 14. The upper end of this rod is pointed to adapt it to coact with the upper pivot-rod 12, and the pointed ends of these pivot-rods are preferably jeweled to provide the required bearing for the needle.

Above the needle 13 and parallel thereto is a disk 16, supported upon brackets 17, projecting inwardly from the standards 9 and having a central opening 18, through which the upper pivot-rod 12 passes.

The disk 16 and the standards are of metal, and upon said disk is a binding-post 19 to secure electrical conductor 20, connected to one side of a battery. (Not shown.) The disk 16 is insulated from the brackets 17 and standards 9.

Extending through an opening in the needle 13 is a rod 21, serving as a circuit-closer and carrying at its upper end a buffer-spring arranged in the form of a loop 22. The circuit-closer 21 also extends through the vertically-aligned hubs 23 of a guide comprising two rectangular frames 24, disposed at right angles to each other, providing a light and effective guide-frame. The rod 21 is insulated from the needle 13 and from the hubs of the guide-frame by bushings of non-conducting material.

The chamber 5 is formed at its upper edge with an annular shoulder 25, serving as a seat for a movable commutator-disk 26, of non-conducting material, having a central opening for the passage of the lower pivot-rod 14 and carrying on its upper surface a series of segments 27, of conducting material, serving as electrical contact-points and each having a separate electrical connection, as shown at 28, with an annunciator or indicator carried on the submerged boat. From the under side of the disk 26 depend two parallel rods 29, extending through the passages 8 of the base and connected at their lower ends by a cross-rod 30, from which depends a rod 31, carrying an armature 32, arranged

within the box or casing 3. Two electromagnets 33 are secured within the box 3 above the armature 32. The upward movement of the rod 31 is limited by a head 34, formed in the end of the said rod, and the downward movement of said rod 31 and the parts attached thereto is limited by a collar 35 on said rod below the armature.

The circuit-closer 21 and its guide-frame 10 are shown suspended adjacent to the north end of the needle; but this location of said parts is not essential, as they may be applied near the opposite end of the needle, if desired.

15 The operation of the mechanism constructed as above described is as follows: The normal position of the commutator-disk 26 is upon its seat 25, as shown by the full lines in Fig. 2; but when the operator on the 20 vessel desires to take his bearing he raises the disk 26 by the electrical means shown for this purpose. To raise the disk by the means shown in Fig. 2, an electrical circuit in which the magnets 33 are included is closed, 25 thus energizing said magnets. The magnets attract the armature 32, and, as is obvious, the raising of the armature raises the commutator-disk 26 through the rod 31 and rods 29. This raising of the disk brings one of 30 its contact-segments 27 into electrical contact with the circuit-closer 21 to close a circuit through the aneroidicator on the vessel, and the position of the needle 13 is thus indicated on board the vessel. The spring 22 is 35 adapted to contact with the disk 16 when the circuit-closer is raised to prevent jarring the needle.

I would have it understood that the invention is not restricted to the construction 40 shown in the drawings, as it will be apparent, as has been heretofore stated, that other means than those shown may be employed for raising and lowering the commutator-disk and that other changes and modifications in the construction or relative arrangement of parts may be resorted to without departing from the spirit and scope of the invention.

What I claim, and desire to secure by Letters Patent, is—

50 1. The combination with a tower, of a compass supported thereon, a commutator supported on the base of the compass, means for raising and lowering said commutator, an electric circuit including said commutator, and a circuit-closer carried by the compass-needle adapted to close a circuit through said commutator.

55 2. In a compass, the combination with a

base of a disk supported thereon, a plurality of contact-points on said disk, each having an independent electric connection, means for raising and lowering said disk, a needle supported above the disk, a circuit-closer carried by said needle, and a contact-plate 65 above said circuit-closer.

3. In a compass, the combination with a base, of a frame supported thereon, a commutator-disk on said base, means for raising and lowering said disk, a disk supported 70 within said frame, pivot-rods supported in vertical alinement within said frame, a needle suspended between said rods, a circuit-closing rod carried by said needle, and a guide-frame through which said circuit-closing rod extends.

4. In a compass the combination with a tower, of a base supported thereon, a frame supported upon said base, a commutator-disk on said base, a needle supported within 80 said frame, a contact-disk above said needle a circuit-closing rod extending through said needle, a guide-frame for said rod, a contact-spring at the upper end of said rod, and means for raising and lowering said commutator-disk.

5. In a compass, the combination with a tower, of a base supported thereon, a frame supported upon said base, a commutator-disk on said base, a needle supported within 90 the frame, a contact-disk above said needle, a circuit-closing rod extending through said needle, a guide-frame for said rod, a contact-spring at the upper end of said rod, and means for raising and lowering said commutator-disk, comprising depending rods extending through the frame, an armature connected to said rods, and an electromagnet.

6. In a compass, the combination with a tower, of a base supported thereon, a frame supported upon said base, a commutator-disk on said base, a needle supported within the frame, a contact-disk above said needle, a circuit-closing rod extending through said needle, a guide-frame for said rod, a contact-spring at the upper end of said rod, and means for raising and lowering said commutator-disk comprising a box or casing supported by said tower, an electromagnet and an armature within said box, and rod connections between said armature and said commutator-disk.

In testimony whereof I affix my signature in the presence of two witnesses.

FREDERICK ALBERT STRASSWEG.
